UNITED STATES PATENT OFFICE.

MARTIN HOKANSON, OF DULUTH, MINNESOTA.

APPARATUS FOR SEPARATING SOLID MATERIALS OF DIFFERENT SPECIFIC GRAVITIES.

Application filed July 17, 1918, Serial No. 245,296. Renewed June 29, 1922. Serial No. 571,794.

To all whom it may concern:

Be it known that I, MARTIN HOKANSON, a resident of Duluth, in the county of St. Louis and State of Minnesota, have invented 5 a new and useful Improvement in Apparatus for Separating Solid Materials of Different Specific Gravities, of which the following is a specification.

This invention relates to apparatus for 10 separating and concentrating solid granular materials of different characteristics. One purpose of the invention is to provide apparatus for separating the valuable part of ore from gangue, by subjecting the material, in a finely crushed condition, to the 15 action of an upwardly flowing current of water in a series of vertical chambers, and controlling the water flow so that its velocity in each chamber is just sufficient to carry therethrough the particles of a particular 20 material, the velocity in the next higher cylinder not being sufficient to carry the said heavier particles therethrough, but sufficient to carry the next lighter particles 25 therethrough. That is, each cylinder has a velocity which will not support granular solid material which has been carried through the preceding cylinder. Consequently, at the top of each cylinder the 30 heaviest particles of material carried therethrough are dropped out of the upwardly flowing stream, the other particles being carried on through the next cylinder, the heaviest particles of the remaining mixture 35 being separated out at the top thereof, and so on.

Fig. 1 shows a vertical central section through the apparatus (diagrammatic); Fig. 2 shows a horizontal section on the 40 line 2—2 of Fig. 1; Fig. 3 shows a partial vertical section on an enlarged scale of a portion of the apparatus shown in Fig. 1; Fig. 4 shows a modification of the feed arrangement; and Figs. 5 and 6 show modifications of a supplementary water supply system.

If particles of matter of the same sizes but different weights are exposed to an upward flow of water of decreasing velocity, 50 light particles will be carried farther than heavy particles, and the distance to which the individual particles are transported will vary quite accurately according to their respective specific gravities. A somewhat 55 similar principle is that particles of matter

of the same specific gravity, but of different sizes, will be graded by an upward current of water of decreasing velocity, the smaller particles being carried to the greater distance. This principle has been applied to 60 the grading of sand. In the present case, the first of these principles only is used, namely, an upward current of water is applied to a mixture in which the particles are all substantially of the same size but are 65 of different specific gravities.

The present apparatus is particularly concerned with the separation of the gangue, such as silica, alumina, etc., from iron and other ores. The silica sometimes occurs in 70 a coarse sandy state, sometimes in a very finely divided state, in some forms of ores being so fine that it is necessary to crush the ore so that it will pass a one hundred mesh sieve, or smaller, before the silica particles, etc., will be detached from the iron oxide particles. The ordinary hematite ore when free from silica, has a specific gravity of about two to three. The silica particles having a specific gravity of somewhat less 80 and the alumina is still lighter. Therefore, when particles of ore, and particles of gangue, etc., of the same size are subjected to a vertical current of water, the particles of gangue will be raised by a current of 85 lesser velocity than that required to carry the particles of ore, and this furnishes a very accurate means for separating the one from the other.

It is a known principle that water moving 90 through a pipe under pressure attains its greatest velocity at the center of the pipe, and that near the walls of the pipe the rate of flow is considerably less than at the center. Where a current of water in a pipe is 95 carrying a mixture of uniformly sized particles, there is a tendency for the heavier particles to be thrown outward toward the walls of the pipe into the slower current, and if the particles are of the same specific gravity, 100 but different sizes, the larger particles will be thrown out first.

In the practice of the present invention, iron ore, (or other ores or materials to be 105 subjected to concentration as herein described) is crushed, if necessary, to reduce it to sufficiently small particles to free the gangue, resulting in a loose mechanical mixture. The mixture is graded into sizes, the number of grades depending upon the 110

nature of the material being handled. Each grade is then subjected to separation according to this invention.

The graded mixture of ore and gangue and water is supplied to a receptacle 1, from which it is introduced to the bottom of a vertical cylinder 2, the first of a series of similar separators. It will be understood that the mixture of granular materials and water must be forced upward through the apparatus under pressure. This may be done by situating the mixing receptacle 1 at a height greater than that of the separating apparatus, and connecting the bottom of cylinder 2 to it by a pipe 3. In this case the feeding is done entirely by gravity and is automatic so long as the tank 1 is properly supplied. Instead of this gravity feeding arrangement I may use a force pump, and carry the mixture from any convenient point. A desirable modification of the feeding means is illustrated in Fig. 4, and described below.

The pipe 3 has a vertical extension 4 connected to an inverted conical portion 5, forming the lower end of cylinder 2. This first cylinder is of such length as to subject the mixture to the separating influence of the upward flowing current for sufficient time to throw the heavy particles to the outside. This cylinder forms a chamber A.

Surrounding the upper end of cylinder 2 is an enlarged casing or jacket 6, the lower end of which is supported by the cylinder 2, and the upper end of which forms an aligned vertical cylinder 7. Thus an enlarged chamber B is formed around the upper end of cylinder 2, and below this, and surrounding the cylinder is an annular pocket, C. The cylinder 7 forms a chamber D, which in turn leads into an enlarged chamber E, formed by a casing or jacket 8, surrounding the upper end of cylinder 7 and supported thereby just as the casing 6 surrounds and is supported by the cylinder 2. The casing 8 forms an annular pocket F about the top of cylinder 7, and extends upward as a third vertical aligned cylinder 9, forming the cylindrical chamber G. The upper end of this third cylinder is surrounded by an enlarged circular tank 10, which forms an overflow basin H, around the upper end of cylinder 9.

The bottom 11 of the annular pocket C formed by the junction of casing 6 and cylinder 2 is provided with perforations 12. Fitted into these perforations are nozzles 13 having their upper ends flush with the bottom 11 and their lower ends curved and pointing in the direction of inclination of the bottom 14 of a draw-off chamber I which is situated immediately beneath the perforated bottom 11. The bottom 14 and walls of the chamber I are inclined in each direc-

tion around the chamber A so that said chamber I increases in size to the point where it empties into a draw-off port 15, which leads by a suitable pipe 16 to any desired point. Directly opposite the draw-off port 15, and at the smallest part of the chamber I, is an inlet port 17, to which is connected a pipe 18 controlled by valve 19.

The same arrangement of draw-off chamber, perforated bottom, and inlet and outlet ports therefor are provided at the junction of casing 8 and cylinder 7, as illustrated in the drawing, and indicated by similar reference numerals having the letter *a* added, except for the annular draw-off compartment marked J.

The overflow compartment H is provided with a suitable drain pipe 20.

It will be understood that the pipes 16, 16^a, and 20 are led to any suitable place for discharge of the material, and are provided with the necessary valved connections therefor.

In a former application Serial No. 207,001, filed December 13, 1917, I have described apparatus somewhat similar to this, and having similar objects, in which each of the succeeding cylindrical chambers corresponding to A, D, and C, is larger than its preceding cylinder. This was for the purpose of securing a decreased flow of liquid in each succeeding cylinder, so as to cause the throwing out of the heavier particles at the top of the first cylinder, and so on. I have found, however, that with certain mixtures, and materials of certain composition, a sufficient quantity of water is drawn off around the top of the first cylinder 2, to secure the necessary decrease of velocity in the cylinder 7, for the purpose of separation. In theory, the apparatus is designed so that the heaviest particles will be just barely carried to the top of the chamber A, by the velocity of flow therein, and will be thrown out into the enlarged chamber B, falling into the pocket C, and removed through draw-off chamber I and pipe 16. Now, a certain amount of water is carried off with the heavier particles with this operation, and consequently the volume of water flowing upward through chamber D is less than that in chamber A. Since, theoretically, the velocity of chamber D should be just sufficient to raise the particles of next greatest specific gravity to the top of that chamber, it is essential that the velocity of flow in chamber D be less than in chamber A, but still it must be great enough to raise the second class of particles to the top thereof. In order to compensate for the loss of water about the top of the first cylinder, I find that the second cylinder must often be as small as the first, or even smaller, in order to maintain the desired velocity therein. Consequently, in this apparatus, the succeed-

ing cylinders are not necessarily larger, but may be made of approximately the same size, or of even smaller size successively, according to the circumstances and materials of each case.

It is necessary to accurately measure the comparative specific gravities of the materials being separated, to determine the proportion of each constituent of the mixture, 10 and to regulate carefully the velocities in the several cylinders in order to give the required velocities in the several cylinders to secure an efficient separation.

For this purpose I prefer to provide cylinders of approximately the same size, and regulate the velocities of flow in each one by means of controlling the amount of water drawn off between cylinders.

This is done by means of valves 21 and 20 21^a in the draw-off pipes 16 and 16^a, and by supplying additional water to the draw-off compartments I and J by means of the pipes 18 and 18^a. Manifestly, the rate of escape of water through the ports 12 and 12^a is 25 dependent upon the discharge of water from the compartments I and J. If the water introduced from the ports 18 and 18^a is equal to the amount flowing out the pipes 15 and 15^a, then there can be no escape 30 through 12 and 12^a. Consequently, these supplementary supplies of water must be so regulated as to accurately control the discharge from the concentrating apparatus at each draw-off point. By this means, the 35 velocity of flow in each of the chambers A and D can be accurately regulated, and varied to suit the proportions and weights of the materials being separated.

The operation of the apparatus is as follows: Any kind of ore from which the gangue is to be separated (or other mechanical mixture of fine materials of different specific gravities) is crushed and accurately graded to a uniform size. The 40 required size varies according to the nature of the ore or other material to be separated. The graded mixture is then placed in the receptacle, 1, and mixed with water to carry it. This mixture flows by gravity 45 through pipe 3 and upward through cylinder 2. The particles of greatest specific gravity will be thrown to the outside of the chamber A as the mixture passes therethrough, and upon reaching the enlarged 50 chamber B, the heavier particles at the outside of the stream will be thrown outward. The rate of flow being suddenly decreased, the upward stream will not be sufficient to support the heavy particles and they fall 55 into the annular chamber C, settle to the bottom thereof and escape through the nozzles 13 into the draw-off chamber I and through the pipe 16. The constant outflow from the 60 bottom of chamber C produces a slight downward current in said chamber, which

assists in leading the heavy particles into said chamber and down to the discharge orifices. The amount of water, and the size of the chambers B and D are so related that all but the heaviest particles are carried on upward through the cylinder 7, and into the chamber E. Here again the heavier particles are no longer supported by the flow of water and fall outward around the top of cylinder 7 75 into the pocket F, and are drawn off just as above described. The very light material is again carried on through the cylinder 9, and finally flows off by way of pipe 20 to be discharged at any suitable place. Or 80 a third separating arrangement can be used to clean the water, so that it may be used over again, as in localities where water is scarce.

In my prior application above referred to I show a centrifugal pump for forcing the mixture through the separating apparatus. The mixture of ore and water has a rapid wearing effect on the pump casing, and therefore I prefer to use the gravity feed 85 above described. However, in some cases a pump feed may be desirable. By providing a tank 30, (Fig. 3) adapted to receive the mixture of ore and water, and connecting it to the bottom of cylinder 2 by a pipe 90 31, and leading a horizontal branch 32 into the pipe 31, water may be pumped into the apparatus so as to give sufficient pressure and velocity to the mixture, regardless of the elevation of mixing tank 30. Any form 95 of pump may be used, though I have illustrated a centrifugal pump 33.

In this modification it is better to introduce water from pump 33 in the form of a jet under high pressure, to get an injector action. To this end pipes 31 and 32 are reduced in size toward their meeting ends and an interior nozzle 34 is led into pipe 32 from pump 33. The end of this nozzle 100 extends nearly to the restricted portion lying at the junction of pipes 31 and 32. Consequently, the stream of clear water from nozzle 34 will carry the mixture from tank 30 into pipe 31 and into the separating apparatus, under sufficient pressure to move it through the apparatus.

In order to keep the mixture of water and solid particles in tank 30 uniform, I may provide an agitator, comprising a vertical shaft 35 having lateral paddles 36 thereon, 110 in the tank. This may be driven by any suitable means, such as by belt pulleys 51, or operated intermittently by hand.

In order to supply water and solids in proper proportions I provide a water supply pipe 50 having a control valve 37, and a granular supply pipe 38, having a control gate 39 therein.

In Figs. 5 and 6, I show modifications 125 of the supplementary water supply means.

In Fig. 5, a water pipe 40 controlled by valve 41 leads into the enlarged casings 6 just above the top of cylinder 2, and is connected to an annular pipe 42 extending 5 around the chamber B as shown. The underside of pipe 42 is perforated, as shown, so that water therefrom is forced downward, thus aiding the separating current above described in leading the heavy particles into chamber C. A similar arrangement 10 may be provided for chamber E.

Near the bottom 11 of chamber C another pipe 43 having a control valve 44, leads through the casing to a circular perforated 15 pipe 45 in chamber C. The perforations in pipe 45 are on the lower side thereof and are situated respectively just above nozzles 13, so as to aid in driving out the solids therethrough. A similar arrangement 20 may be provided for chamber F.

Instead of placing pipe 42 inside the chamber B, I may make an offset 45 in the wall of casing 6, as shown in Fig. 6, and place pipe 42^a on the outside and lead small 25 nipples 46 to the inside of chamber B.

Any desired combination of these modified features may be provided and used. Or they may all be attached to a standard apparatus, and used or not according to the 30 particular circumstances of each case.

It will be obvious that the means provided allow very accurate adjustment of the rate of flow in each chamber.

It will be understood that the drawings 35 are merely illustrative of my apparatus, and the proportions of the various compartments are not intended to be fixed by the dimensions shown. For instance, the cylinder 7 may be longer than the cylinder 2, if desired, 40 and larger or smaller in diameter than that cylinder. Likewise, the cylinder 9, which is here shown as very short, and in effect merely an outlet from chamber E, may be prolonged, and provided with draw-off 45 connections and compartments similar to those about the tops of cylinders 2 and 7.

The apparatus is not limited to the separation of iron ore, but may be used for any mixture of ore and gangue, or in fact for 50 any mechanical mixture of particles of different specific gravities, where the difference in specific gravities is large, and the size of the particles the same, or nearly so.

The method carried out by the above described process is not claimed herein but is claimed in my application Serial No. 272,327, filed Jan. 21, 1919.

I claim:

1. Apparatus for separating solid granular materials, comprising a vertical vessel, 60 means for forcing the materials in a finely divided form mixed with water upwardly through said vessel, said vessel intermediate its height being provided with a portion of 65 increasing diameter providing an annular

chamber in which the solids are deposited by radial separation from the vertical stream, said annular enlargement being provided with a series of outlets uniformly spaced around said vessel, an annular chamber receiving from said discharge openings, said annular chamber being of progressively increasing dimensions from one side, and a controllable outlet from the largest point of said draw-off chamber. 75

2. Apparatus for separating solid granular materials, comprising a vertical vessel, means for forcing the materials in a finely divided form mixed with water upwardly through said vessel, said vessel intermediate 80 its height being provided with a portion of increasing diameter providing an annular chamber in which the solids are deposited by radial separation from the vertical stream, said annular enlargement being 85 provided with a series of outlets uniformly spaced around said vessel, means for regulating the amount of water drawn off through said discharge openings, and means to introduce an additional supply of water 90 to said vessel adjacent the withdrawal point.

3. Apparatus for separating solid granular materials, comprising a vertical vessel, means for forcing the materials in a finely divided form mixed with water upwardly 95 through said vessel, said vessel intermediate its height being provided with a portion of increasing diameter providing an annular chamber in which the solids are deposited by radial separation from the vertical stream, said annular enlargement being provided with a series of outlets uniformly spaced around said vessel, an annular draw-off chamber receiving from said openings and being of progressively increasing dimension 100 from one side, a withdrawal outlet from the largest point of said draw-off chamber, and an additional water supply connected to said draw-off chamber. 105

4. Apparatus for separating solid granular materials, comprising a vertical vessel, means for forcing the materials in a finely divided form mixed with water upwardly through said vessel, said vessel intermediate 115 its height being provided with a portion of increasing diameter providing an annular chamber in which the solids are deposited by radial separation from the vertical stream, said annular enlargement being provided with a series of outlets uniformly 120 spaced around said vessel, an annular draw-off chamber receiving from said discharge openings and being of increasing dimensions from one side, an outlet at the largest point of said draw-off chamber, and means for introducing an additional water supply adjacent to said draw-off openings and so related thereto as to induce a current through said draw-off openings. 125

5. Apparatus for separating solid granu- 130

lar materials, comprising a vertical vessel, means for forcing the material in a finely divided form mixed with water upwardly through said vessel, said vessel intermediate 5 its height being provided with a portion of increasing diameter providing an annular chamber in which the solids are deposited by radial separation from the vertical stream, said annular enlargement being provided with a series of outlets uniformly spaced around said vessel, an annular draw-off chamber receiving from said discharge openings and being of progressively increasing dimension from one side, a discharge 10 outlet from the largest point of said draw-off chamber, and nozzles in said discharge openings projecting into the draw-off chamber and directed toward the discharge opening therefrom.

15

20 6. Apparatus for separating solid granular materials, comprising a vertical vessel, means for forcing the material in a finely divided form mixed with water upwardly through said vessel, said vessel intermediate 25 its height being provided with a portion of increasing diameter providing an annular chamber in which the solids are deposited by radial separation from the vertical stream, said annular enlargement being provided with a series of outlets uniformly spaced around said vessel, an annular draw-off chamber receiving from said discharge openings and being of progressively increasing dimension from one side, a discharge 30 outlet from the largest point of said draw-off chamber, nozzles in said discharge openings projecting into the draw-off chamber and directed toward the discharge opening therefrom, and a water supply connected 35 to said draw-off chamber and directing the current in the direction of the nozzles.

40

7. Apparatus for separating solid granular materials, comprising a vertical vessel, means for forcing the materials in a finely 45 divided form mixed with water upwardly through said vessel, said vessel intermediate its height being provided with a portion of increasing diameter providing an annular chamber in which the solids are deposited by 50 radial separation from the vertical stream, said annular enlargement being provided with a series of outlets uniformly spaced around said vessel, an annular draw-off chamber receiving from said openings and 55 being of progressively increasing dimension from one side, a withdrawal outlet from the largest point of said draw-off chamber, an additional water supply connected to said draw-off chamber, and further water supply 60 to the upper portion of said annular enlargement.

8. Apparatus for separating solid granular materials, comprising a vertical vessel, means for forcing the material in a finely divided form mixed with water upwardly 65

through said vessel, said vessel intermediate its height being provided with a portion of increasing diameter providing an annular chamber in which the solids are deposited by radial separation from the vertical stream, 70 said annular enlargement being provided with a series of outlets uniformly spaced around said vessel, an annular draw-off chamber receiving from said discharge openings and being of increasing dimension at 75 one point, an outlet at the largest point of said draw-off chamber, means for introducing an additional water supply adjacent to said draw-off openings and so related thereto as to induce a current through said draw-off openings, and a further water supply to the upper portion of said annular enlargement.

9. Apparatus for separating solid granular materials, comprising a vertical cylindrical vessel, means for forcing the material in a finely divided form mixed with water upwardly through said vessel, a second vessel above the first vessel and having its lower end extending below and of larger diameter 85 than the top of the first vessel, thereby providing an annular chamber in which the solids are deposited by radial separation from the vertical stream, the upper end of the first vessel curving progressively outwardly, 90 said annular chamber being provided with a series of outlets uniformly spaced around said vessel, an annular chamber receiving from said discharge openings, said annular chamber being of progressively increasing 95 dimensions from one side, and a controllable outlet from the largest point of said draw-off chamber.

10. Apparatus for separating solid granular materials, comprising a vertical cylindrical vessel, means for forcing the material in a finely divided form mixed with water upwardly through said vessel, a second vessel above the first vessel and having its lower end extending below and of larger diameter 105 than the top of the first vessel, thereby providing an annular chamber in which the solids are deposited by radial separation from the vertical stream, the top of the first vessel curving progressively outwardly, said 110 annular chamber being provided with a series of outlets uniformly spaced around said vessel, means for regulating the amount of water drawn off through said discharge openings, and means to introduce an additional supply of water to said vessel adjacent 115 the withdrawal point.

11. Apparatus for separating granular materials of different characteristics, comprising a vertical cylinder, means to introduce a stream of water carrying the materials to be separated to the bottom of the said cylinder, a casing surrounding the top of the said cylinder and attached to the outer wall thereof below the top, draw-off 125

ports at the junction of the casing and cylinder wall, means to regulate the amount of water drawn from the apparatus through said ports, means to introduce a regulated amount of water above said draw-off ports, and a second cylinder leading upward from the said casing.

12. Apparatus for separating granular materials of different characteristics, comprising a storage receptacle for a mixture of water and the granular materials, means to force the mixture from the storage receptacle to the bottom of a vertical cylinder, an enlarged casing about the top of the said cylinder, means to draw off solid material deposited in said casing at the top of the first cylinder, means to regulate the amount of water drawn off with said solid material, means to introduce a supplementary supply of water to said casing, and a series of succeeding axially aligned cylinders and casings having similar drawing off and water supplying means.

13. Apparatus for separating a mixture of solids of different characteristics, comprising a vertical cylinder, means to introduce the mixture in a stream of water to the bottom of the cylinder, an enlarged casing about the top of the cylinder and connected to the outer wall thereof below the top, perforations in the casing wall at its bottom, an annular chamber surrounding the connections between the casing and the cylinder wall, an escape port from the draw-off chamber, and a valved inlet pipe thereto connected to a water supply.

14. Apparatus for separating granular materials of different characteristics, comprising a series of vertically arranged cylinders having enlarged chambers about the top of each cylinder, means to draw off granular material from each enlarged chamber, and means to supply additional water at each draw-off level to compensate for that drawn off with the granular material.

15. Apparatus for separating granular materials of different characteristics, comprising a series of vertically-arranged upward-flow cylinders, an enlarged settlement chamber connecting each cylinder to the cylinder next above, a series of perforations in the bottoms of said settlement chambers adapted to carry off granular material deposited there, an annular draw-off chamber beneath each settlement chamber and connected thereto by said perforations, an outlet from said draw-off chamber to carry off granular material and water and an inlet thereto to supply water to compensate for the water discharged from the draw-off chamber.

16. Apparatus for separating granular materials of different characteristics, comprising a series of vertically-arranged upward-flow cylinders, an enlarged settlement

chamber connecting each cylinder to the cylinder next above, a series of perforations in the bottoms of said settlement chambers adapted to carry off granular material deposited there, an annular draw-off chamber beneath each settlement chamber and connected thereto by said perforations, an outlet from said draw-off chamber to carry off granular material and water, an inlet thereto to supply water to compensate for the water discharged from the draw-off chamber, and means to control the amount of water supplied to the draw-off chamber.

17. Apparatus for separating solid materials comprising in combination, a vertical casing, a second casing above the said first casing and having its lower end of larger diameter than the top of the first casing and extending below the top of the first casing and forming an annular chamber there-around, means for forcing the material in a finely divided form mixed with water upwardly through said casings, and a constantly open outlet from said annular chamber.

18. Apparatus for separating solid materials comprising in combination, a vertical casing, a second casing above the said first casing and having its lower end of larger diameter than the top of the first casing and extending below the top of the first casing and forming an annular chamber there-around, means for forcing the material in a finely divided form mixed with water upwardly through said casings, and a series of constantly open withdrawal openings in the bottom of said annular chamber and entirely around the same.

19. Apparatus for separating solid materials comprising in combination, a vertical casing, a second casing above the said first casing and having its lower end of larger diameter than the top of the first casing and extending below the top of the first casing and forming an annular chamber there-around, means for forcing the material in a finely divided form mixed with water upwardly through said casings, the bottom of said annular chamber being provided with a series of withdrawal openings extending entirely around the same, an annular withdrawal chamber below said perforated bottom and receiving the discharge from said openings, and a constantly open draw-off outlet from said last named chamber.

20. Apparatus for separating solid materials comprising in combination, a vertical casing, a second casing above the said first casing and having its lower end of larger diameter than the top of the first casing and extending below the top of the first casing and forming an annular chamber there-around, the bottom of said annular chamber being provided with a series of withdrawal openings extending entirely around the

same, means for forcing the material in a finely divided form mixed with water upwardly through said casings, an annular draw-off chamber below said perforated bottom and receiving the discharge from said openings and being of progressively increasing dimension from one side in both directions to the other side, and an outlet from the largest point in the said draw-off chamber.

21. Apparatus for separating solid materials comprising in combination, a vertical casing, a second casing above said first casing and having its lower end of larger diameter than the top of the first casing and extending below the top of the first casing and forming an annular chamber around the first casing, a third casing above the second casing and having its lower end of larger diameter than the top of the second casing and extending below the top of the second casing and forming an annular chamber therearound, means for forcing the material in a finely divided form mixed with water upwardly through said casings, and constantly open outlets from both of said annular chambers.

22. Apparatus for separating solid mate-

rials comprising in combination, a vertical casing, a second casing above the said first casing and having its lower end of larger diameter than the top of the first casing and extending below the top of the first casing and forming an annular chamber around the first casing, a third casing above the second casing and having its lower end of larger diameter than the top of the second casing and extending below the top of the second casing and forming an annular chamber therearound, means for forcing the material in a finely divided form mixed with water upwardly through said casings, the bottoms of each of said annular chambers being provided with discharge openings extending entirely around the same, an annular withdrawal chamber below each of said perforated bottoms and receiving the discharge therethrough and being of progressively increasing dimension from one side in both directions to the other side, and a draw-off outlet from the largest point of each of said draw-off annular chambers.

In testimony whereof, I have hereunto set my hand.

MARTIN HOKANSON.
